DESIGN FOR A CIGARETTE CASE

Emil Lackow, Brooklyn, N. Y.

Application June 12, 1934, Serial No. 52,147

Term of patent 3½ years

To all whom it may concern:

Be it known that Emil Lackow, a citizen of the United States and resident of Brooklyn, in the county of Kings and State of New York, has invented a new, original, and ornamental Design for Cigarette Cases, of which the following is a specification, reference being had to the accompanying drawing, forming part thereof, in which, Figure 1 is an elevation showing the exterior of the cigarette case when wide open; Figure 2 is an elevation showing the opening edge of the cigarette case; Figure 3 is an elevation showing the interior of the cigarette case when wide open; Figure 4 is an elevation similar to Figure 2 with the exception that the case is partially open.

I claim:

The ornamental design for a cigarette case substantially as shown and described.

Dated, June 6th, 1934.

EMIL LACKOW.
